UNITED STATES PATENT OFFICE.

JOSHUA WHITTEMORE, OF SOUTH READING, MASSACHUSETTS.

IMPROVEMENT IN CRUTCHES.

Specification forming part of Letters Patent No. 36,743, dated October 21, 1862.

To all whom it may concern:

Be it known that I, JOSHUA WHITTEMORE, a citizen of the United States of America, and a resident of South Reading, in the county of Middlesex and State of Massachusetts, have made an invention of certain new and useful Improvements in Crutches for the Use of Lame Persons; and I do hereby declare the same to be fully described in the following specification and represented in the accompanying drawings, of which—

Figure 1 denotes an elevation or side view, and Fig. 2 a longitudinal section, of a crutch provided with my invention.

The stand or body of the crutch is composed of two separate springs, A A, made of lance-wood or other suitable material, and shaped or formed as shown in Fig. 1. These springs, at or near their lower ends, are brought together and inserted within a ferrule or socket-piece, C, above which and at the vertex of their angle of departure they are encompassed by a ring or band, D, of metal. At their upper ends the two springs are so connected to the two extremities of a flexible arm-rest, E, which is a cushion or stuffed pad, that when the crutch is in use goes under the shoulder-joint of a person and serves as a support thereto. Whenever the weight of the body of the person using the crutch is borne upon the flexible rest E, the latter will be caused to bend under the same and draw the upper portions of the two springs A A inward toward each other and against an abutment-bar, F, extended from one to the other of them, and about midway between the band D and the said arm-rest E. The springs not only perform the function of giving support to the body of a person, but co-operate with the flexible arm-rest in producing an elastic bearing for the arm.

Within the lower part of the crutch is a tapering socket, a, in the upper part of which there is a screw-nut, b, for receiving a male screw, c, which projects upward from a jawed socket-piece, H. This latter is made with a chamber or recess, d, having a dovetailed form. A round block or buffer, I, composed of vulcanized india-rubber or other suitable elastic equivalent, is inserted within and made to project out of such recess d, in manner as shown

in Fig. 2. Above the recess d the jawed socket is formed so as to receive and grasp the shank of a metallic spur, K, which extends down either through or into the middle part of the elastic buffer.

The jawed socket-piece H is slit longitudinally by two crossed slits, e e, arranged at right angles to each other, and is made with a tapering form externally and below the screw c, as shown in the drawings.

Fig. 3 is a view of the lower end of the crutch and shows the arrangement of the slits e e, the elastic buffer, and the spur. Fig. 4 is a side view of the jawed socket-piece H and its slits.

By revolving the jawed socket-piece within the crutch-ferrule, so as to cause the screw c to enter the nut b, the jaws of the socket-piece will be closed upon both the spur and the buffer, so as to hold them firmly in place.

The buffer not only renders the crutch easier to a person while using it, but operates to prevent the foot of the crutch from slipping on ice or any smooth surface. The spur is an additional preventive also against slipping of the crutch, particularly when the surface borne upon may be wet. The buffer, while a person may be in the act of using the crutch, will not only relieve him from the concussions incident to the downward blows of the crutch, but will operate to prevent the noise which ordinarily results from a solid foot of a crutch while in use.

I claim—

1. The crutch, as made of two separate spring-bars, A A, and the flexible arm-rest E, substantially as specified.
2. The india-rubber or elastic buffer I, in combination with the crutch provided with a socket or buffer-holder.
3. The combination of the spur K with the elastic buffer and the crutch.
4. The jawed socket-piece, made in manner and to operate as explained, in combination with the crutch, elastic buffer, and the spur substantially as described.

JOSHUA WHITTEMORE.
